UNITED STATES PATENT OFFICE.

ALBERT J. MARKS, OF BOSTON, MASSACHUSETTS, ASSIGNOR TO AJAX TIME STAMP COMPANY, OF BOSTON, MASSACHUSETTS, A CORPORATION OF MASSACHUSETTS.

STAMPING DEVICE.

Application filed April 9, 1927. Serial No. 182,278.

My present invention relates to stamping devices, and more particularly to an improvement in stamping devices of such a type as is shown in the co-pending case of 5 Joseph Levy, Serial No. 135,583, filed Sept. 15, 1926.

Heretofore in devices of this kind, difficulty has been experienced due to the fact that, upon pressing down upon the handle 10 to operate the stamp, the spring that regulates the return action caused a chattering action, often rebounding to such an extent that the original stamp impression would be blurred. And in work of this kind, 15 where a clear print is very essential, blurring is most objectionable.

This chattering has also tended to loosen the mechanism and increase wear, thus inevitably having a weakening effect on all 20 parts of the device.

In my present invention I have endeavored to overcome these objectionable features, and thus have devised an automatic checking, braking, holding, or controlling 25 device which effectually prevents chattering, wear, blurring, or the like.

In carrying out my invention, I have applied a simple, efficient, and conveniently 30 positioned spring or member, so constructed and arranged as to engage a portion of the moving part of the stamping device, to act as a yielding brake or check, when the handle is released, and the returning spring acts. This yielding brake or check may be 35 in the form of a forked or two-arm spring, shaped and positioned to straddle and grip or hold the lower part of the movable or pivoted member carrying certain of the stamping means. This spring acts in opposition to the main spring which both 40 raises and tends to keep the movable portion of the stamping apparatus in raised position, and is so designed as to eliminate completely all chattering effects, and all 45 vibration, preventing any reflex action. My invention also aids in preventing wear on the mechanism, and acts as a combined braking, holding, and steadyng means.

In the accompanying drawing illustrating 50 a preferred embodiment of my invention, Fig. 1 is a side elevation;

Fig. 2 is a fragmentary cross sectional view on the line 2—2 of Fig. 1

Referring to the drawings, 10 designates a 55 hollow base having formed integral there-

with, and at one end thereof, a pair of spaced ears 11, in which is pivotally mounted a carrying arm 12. At the outer end of said arm 12 is an ordinary stamping mechanism enclosed in a box-like casing 17, with a resilient striking pad 18 preferably of rubber surmounted thereon, as a striking handle for the operator. By striking this pad 18, the outer end of the arm 17 is forced downwardly in contact with the 60 platen 19, thus effecting the stamping process on any interposed paper, such as a check, letter, bill, or the like.

Formed integral with the carrying arm 12, and extending downwardly therefrom, 70 adjacent its pivot connection with the ears 11, is a depending arm 13, which extends downwardly through a perforation 14 in the base 10. Secured to the lower end of the arm 13 is one end of a coil spring 15, 75 the other end of this spring being connected to a fixed part of the base 10, as at the lower end of a lug 16, as clearly shown in the drawing. The spring 15 yieldingly holds the arm 12 in the position shown in Fig. 1, 80 and tends to return said arm 12, and all parts attached thereto, after a stamping operation, to raised position, as shown in Fig. 1.

Under the surface of the hollow base 10, and in contact with the lower portion of 85 the arm 13 is a forked two arm spring 20 secured and fulcrumed by the screw 21, the two arms 22 and 23 of said spring 20 straddling the lower converging portion of the arm 13. These arms 22 and 23 are so designed that they not only allow the arm 13 to be checked by them with a constantly increasing tension and resistance, but they also grip said arm 13 in order to keep it 90 from snapping back from any rebound no matter how hard the pad 18 may be struck to effect the stamping operation.

This spring 20 is thus formed to prevent any chattering or vibrating of the device, thereby saving it from undue wear, or blurring or marring the work.

My invention is further defined in the form of claims as follows:

1. A stamping mechanism of the kind described, comprising a base having a recess 105 therein, a stamping member pivotally connected with said base, a portion of said stamping member depending through said recess, a spring in said base to hold said stamping member in inoperative position, 110

and an adjacent supplemental spring engaging said depending portion of said pivotal member and so arranged as to impart increasing resistance to said pivoted member as the main spring returns said pivoted member to normal position.

2. A stamping device of the kind described, comprising a pivoted carrying arm, stamping mechanism at one end of said arm, 10 a depending arm at the other end of said arm, a contractile spring acting on said depending arm to keep the stamping devices normally raised and to return them to raised position after a stamping operation, and a 15 two-arm spring adapted to straddle the depending arm and impart an increasing braking tension and resistance to said depending arm and said carrying arm as the same are returned to normal position by said contractile spring.

3. A stamping device of the kind described, comprising a hollow base having a recess therethrough adjacent to one end thereof, an upstanding ear at each side of 25 said recess, an arm pivoted to said ears, an arm depending from said first arm and projecting through said recess, a depending lug in said hollow base, a spring engaging said lug and said depending arm to normally

hold said first arm in raised position, and a 30 second spring secured to said base and comprising a pair of arms adapted to straddle and constantly engage said depending arm and to impart a constantly increasing resistance on said depending arm as said depending arm is returned to normal position by 35 said first spring.

4. A stamping device of the kind described, comprising a hollow base having a 40 recess therethrough adjacent to one end thereof, an upstanding ear at each side of said recess, an arm pivoted to said ears, an arm depending from said first arm and projecting through said recess, a depending lug in said hollow base, a spring engaging said 45 lug and said depending arm to normally hold said first arm in raised position, and a second spring secured to the under side of said base and at one side of said recess and comprising a pair of arms adapted to 50 straddle and constantly engage said depending arm and to impart a constantly increasing resistance on said depending arm as said depending arm is returned to normal position by 55 said first spring.

In testimony whereof, I have signed my name to this specification.

ALBERT J. MARKS.
